(57) **CLAIM**

The ornamental design for a display screen or portion thereof with graphical user interface as shown and described.

DESCRIPTION

FIG. 1 is a front view of a first embodiment of a display screen or portion thereof with a graphical user interface embodying the new design; and,

FIG. 2 is a front view of a second embodiment of a display screen or portion thereof with a graphical user interface embodying the new design.

Broken lines are used to illustrate features which form no part of the claimed design.

1 Claim, 2 Drawing Sheets
